PROCESS OF PRODUCING 1-PHENYL-2,3-DIMETHYL-5-PYRAZOLONE

Baptist Reuter, Krailling-Planegg, Germany

No Drawing. Application November 28, 1932,
Serial No. 644,747. In Germany April 12,
1928

13 Claims. (Cl. 260—45)

1-phenyl-3-methyl-5-pyrazolone is usually methylated on a technical scale by dissolving it in methyl alcohol and heating it together with alkyl halides under high pressure. When ethyl bromide is used in this process several drawbacks are involved. This substance has a very low boiling point and is poisonous so that the use of same in some cases has caused the death of persons handling it. Moreover, the methylation with alkyl halides must be performed in enamelled vessels which relatively frequently must be renewed. During the series of operations, the autoclaves must also from time to time be tightened again in order to avoid losses of alkyl halides and the escape of dangerous gases. In the autoclaves the explosive methyl ether is formed and the methylation is driven beyond the dimethyl compound.

In the Bulletin de la Société Chimique, vol. 20 (4) 39, page 321, Rodionow has given some short informations about the effect exerted by p-toluene-sulfonic-acid methyl ester on technical pyrazolone when no solvent is present. He describes merely the formation of a compound which has a solidification point of 91—92° C. and which he regards as the methyl-p-toluene-sulfonate of the pyrazolone.

I have now found that in the melt an intermediate product is formed, which is not obtained in the form of 1-phenyl-2,3-dimethyl-5-pyrazolone when working in the usual manner. When working after the usual method, which comprises the steps of adding alkali to the melt and shaking the oil together with the benzene, this intermediate product is obtained in the form of a dark oil, which is insoluble in benzene and is not obtained in the form of a p-toluene-sulfonic-acid salt at the separation. The intermediate or by-products include compounds which possess the following formulae:

These compounds formed in addition to the 1-phenyl-2,3-dimethyl-5-pyrazolone in the melt are described in the following description and claims as quaternary bases, by-products, or intermediate products. By treating these compounds separately or still better by treating the total methylated melt for about 2 hours at 100° C. with alkalies in excess said compounds will be completely converted into 1-phenyl-2,3-dimethyl-5-pyrazolone. When methylating without this alkali treatment only yields of about 83% of 1-phenyl-2,3-dimethyl-5-pyrazolone are obtained. Through the said treatment, however, the yield of 1-phenyl-2,3-dimethyl-5-pyrazolone is increased to 93% and the yield of p-toluene-sulfonic-acid salt is increased even to 95%. According to the information given by Rodionow the yield of toluene-sulfonic-acid salt amounts only to 50%. I have also found, that the toluene-sulfonic-acid salt will separate out almost quantitatively when the solution is made distinctly acid by means of mineral acids.

EXAMPLES

I. METHYLATION WITH P-TOLUENE-SULFONIC-ACID METHYL ESTER

1. Separation of the 1-phenyl-2,3-dimethyl-5-pyrazolone in the form of a p-toluene-sulfonic-acid salt

174 g. of 1-phenyl-3-methyl-5-pyrazolone and 195 g. of p-toluene-sulfonic-acid methyl ester are heated under stirring. At 130° C. a hardly perceptible foaming takes place. The temperature is thereupon raised to 150° C. and maintained at 150—160° C. for about 5—6 hours. The end product is a transparent melt, which is dissolved by adding 150 ccm. of water and 87 g. of a solution of caustic soda (46%). Thereupon additional 44 g. of caustic soda is added, whereby a deposit is formed and the mass is now boiled under stirring for about 2 hours on a reflux cooler. Instead of the caustic soda corresponding amounts of alkali metal carbonates may be used. The charge is cooled and 190 g. of hydrochloric acid (30%) are added under stirring and cooling, whereupon after some time the toluene-sulfonic-acid salt separates out in the form of a precipitate. This substance will also separate out at once when the fluid is activated by means of some crystals of the toluene-sulfonic-

acid salt. In hot water super-saturated solutions of the salt are formed and it is therefore necessary to add traces of the crystallized compound in order to initiate the crystallization. The 5 product is sucked off through a filter and rinsed with water which has been slightly acidulated with hydrochloric acid. The salt is dried in vacuum or at 30-35° C. At still higher temperatures the salt will melt to a vitreous mass. This 10 mass dissolves in boiling water and is difficultly soluble in ligroin, benzene, alcohol and ether as well as in cold water and particularly in water containing some acid. In bicarbonates and other alkaline solvents the salt dissolves 15 very easily. When super-saturating with strong caustic alkalies 1-phenyl-2,3-dimethyl-5-pyrazolone and sodium p-toluene-sulfonate will separate out.

The product is apparently a compound comprising 20 1 molecule of p-toluene-sulfonic-acid, 1 molecule of 1-phenyl-2,3-dimethyl-5-pyrazolone and 2 molecules of crystal water. Yield: 95% of the theoretically calculated amount. The precipitation of the salt may also be performed in 25 two stages by dissolving the methylated melt in 150 ccm. of hot water and allowing the product to crystallize under cooling and stirring after having added hydrochloric acid until reaction is obtained with Congo red. The crystals are, 30 as described above, washed and dried. This is crystallization I. The intermediate products formed at the methylation are in this case present in the filtrate of the crystallization and this must, therefore, also be treated with caustic alkali. The product is evaporated until a highly 35 concentrated fluid is obtained and this fluid is made strongly alkaline and boiled for about 2 hours on a reflux cooler. Thereupon hydrochloric acid is added until an acid reaction is obtained with Congo red, whereupon the product is stirred in cold state for about half an hour, sucked through a filter, rinsed and dried in the manner described above.

This is crystallization II. Before this product 45 is subjected to further treatment, it is mixed with crystallization I.

2. Direct separation of the base from the toluene-sulfonic-acid-ester melt

The methylation melt obtained after Example 50 1 is dissolved in 150 ccm. of water and boiled under stirring for about 2 hours together with 150 g. of a caustic soda solution or a corresponding amount of other strong alkalies. The mass 55 is thereupon cooled to about 70° C. and twice extracted with 500 ccm. of benzene whilst still hot. The 1-phenyl-2,3-dimethyl-5-pyrazolone passes into solution whereas the sodium toluene-sulfonate remains undissolved. The fluid is separated from the sodium toluene sulfonate by suction or centrifugation and washed with benzene. The caustic soda and the benzene solution in the 60 filtrate are also separated. When distilling off the benzene 1-phenyl-2,3-dimethyl-5-pyrazolone 65 is extremely pure state is left.

3. Producing of the base from the p-toluene-sulfonate

378 g. of the salt obtained in accordance with 70 Example 1 are heated together with 120 ccm. of water and 120 g. of a caustic soda solution (35%) for about half an hour in a water bath and extracted with benzene whilst still hot. After the removal of the benzene a very pure 1- 75 phenyl-2,3-dimethyl-5-pyrazolone is left.

II. METHYLATION OF THE 1-PHENYL-3-METHYL-5-PYRAZOLONE WITH DIMETHYL SULFATE

174 g. of 1-phenyl-3-methyl-5-pyrazolone and 120 g. of dimethyl sulphate (95% of the theoretically calculated amount) are mixed and heated very cautiously in order to prevent a sudden reaction. At 100° C. the temperature will automatically be raised to about 130° C. When the increase of temperature ceases the mass is heated to about 155-160° C. and this temperature is maintained for about 6 hours. Thereupon 50 ccm. of water and subsequently 195 g. of a caustic soda solution (35%) are added under stirring and the charge is heated to about 100° C. for 2 hours on a reflux cooler. Instead 15 of a caustic soda solution also other alkalies, such as carbonates or a mixture of alkali hydroxides and carbonates may be used. The base is separated out by means of benzene exactly 20 in the same manner as described in connection with the toluene-sulfonic-acid process. If it is desired to separate out the intermediate product (instead of converting it directly into 1-phenyl-2,3-dimethyl-5-pyrazolone in the manner described above) the melt is dissolved in 50 ccm. 25 of water, whereupon 195 g. of NaOH are added and the product is extracted with benzene without further heating. Between the benzene and the caustic soda solution a dark oil remains in undissolved state and this oil is the intermediate 30 product.

This intermediate product is separated from the benzene and the caustic soda solution, dissolved in thrice the amount of water and heated to about 100° C. together with the excess of alkali for about 2 hours. After this treatment an oil is left which dissolves completely in benzene. When the benzene has distilled off, tests will show that this product is 1-phenyl-2,3-dimethyl-5-pyrazolone. 40

Yield: 90-92% of the theoretically calculated amount.

I claim:

1. A process for producing 1-phenyl-2,3-dimethyl-5-pyrazolone which comprises the steps of reacting 1-phenyl-3-methyl - 5 - pyrazolone with an alkylating agent in the absence of a solvent at an elevated temperature, thereby producing a melt, and treating said melt with an excess amount of a compound of the group consisting of an alkali-metal hydroxide and an alkali-metal carbonate at a temperature of substantially 100° C. for a relatively long period of time. 45

2. A process for producing 1-phenyl-2,3-dimethyl-5-pyrazolone which comprises the steps of reacting 1-phenyl-3-methyl - 5 - pyrazolone with an alkylating agent in the absence of a solvent at an elevated temperature, thereby producing a melt, dissolving said melt, adding there-to a solution of a caustic alkali, extracting said resulting mixture with benzene, separating out the quaternary bases resulting, and treating said quaternary bases with an excess of a compound 50 of the group consisting of an alkali-metal hydroxide and an alkali-metal carbonate at a temperature of substantially 100° C. for a relatively long period of time. 55

3. A process for producing 1-phenyl-2,3-dimethyl-5-pyrazolone which comprises the steps of reacting 1-phenyl-3-methyl - 5 - pyrazolone with p-toluene-sulphonic-acid-methyl-ester in the absence of a solvent at an elevated temperature, thereby producing a melt, dissolving said melt, 70

adding thereto a solution of a caustic alkali, extracting the resultant mixture with benzene, separating out the quaternary bases formed, and treating said quaternary bases with an excess 5 amount of a compound of the group consisting of an alkali-metal hydroxide and an alkali-metal carbonate at a temperature of substantially 100° C. for a relatively long period of time in order to convert said quaternary bases into the desired 10 product.

4. A process for producing 1-phenyl-2,3-dimethyl-5-pyrazolone which comprises the steps of reacting 1-phenyl-3-methyl-5-pyrazolone with dimethyl sulphate in the absence of a solvent at an elevated temperature, thereby producing a melt containing quaternary bases, and then treating said melt with an excess amount of a compound of the group consisting of an alkali-metal hydroxide and an alkali-metal carbonate at a temperature of substantially 100° C. for a relatively long period of time in order to convert the melt containing said quaternary bases into the desired product.

5. A process for producing 1-phenyl-2,3-dimethyl-5-pyrazolone which comprises the steps of reacting 1-phenyl-3-methyl-5-pyrazolone with dimethyl sulphate in the absence of a solvent at an elevated temperature, thereby producing a melt, dissolving said melt, adding there- 25 to a solution of a caustic alkali, extracting with benzene, separating out the quaternary bases resulting, and then treating said bases with an excess amount of a compound of the group consisting of an alkali-metal hydroxide and an alkali-metal carbonate at substantially 100° C. for a relatively long period of time in order to convert said bases into the desired product.

6. A process for producing 1-phenyl-2,3-dimethyl-5-pyrazolone which comprises the steps of reacting 1-phenyl-4-methyl-5-pyrazolone with an alkylating agent in the absence of a solvent at an elevated temperature, thereby producing a melt containing quaternary bases, treating said melt with an excess amount of a compound of the group consisting of an alkali-metal hydroxide and an alkali-metal carbonate at a temperature of substantially 100° C. for a relatively long period of time in order to convert said bases into the desired product, extracting said melt while still warm with benzene, and then removing the benzene to isolate the desired product.

7. A process for producing 1-phenyl-2,3-dimethyl-5-pyrazolone which comprises the steps of reacting 1-phenyl-3-methyl-5-pyrazolone with an alkylating agent in the absence of a solvent at an elevated temperature, thus forming a mixture containing a salt of 1-phenyl-2,3-dimethyl-5-pyrazolone together with quaternary bases, treating said mixture with an excess amount of a compound of the group consisting of an alkali-metal hydroxide and an alkali-metal carbonate at a temperature of substantially 100° C. for a relatively long period of time in order to convert said quaternary bases into the desired product, acidulating the resultant mixture with a mineral acid in order to separate the salt of 1-phenyl-2,3-dimethyl-5-pyrazolone, isolating said salt by filtering, heating it with a solution of a caustic soda for a relatively long period of time, thus forming the desired product, extracting said product while the mixture is still warm with benzene, and then removing the benzene to isolate said product.

8. A process for producing 1-phenyl-2,3-dimethyl-5-pyrazolone which comprises the steps of reacting 1-phenyl-3-methyl-5-pyrazolone with p-toluene-sulphonic-acid-methyl-ester, thereby producing a mixture containing the salt of 1-phenyl-2,3-dimethyl-5-pyrazolone with p-toluene-sulphonic acid together with quaternary bases, adding to said mixture a solution of caustic soda, extracting the resultant mixture with benzene, removing the quaternary bases present in said mixture, treating said quaternary bases with an excess amount of a compound of the group consisting of an alkali-metal hydroxide and an alkali-metal carbonate at a temperature of substantially 100° C. for a relatively long period of time in order to convert said quaternary bases into the desired product, acidulating the mixture from which said quaternary bases have been extracted with a mineral acid in order to separate the p-toluene-sulphonic acid salt of 1-phenyl-2,3-dimethyl-5-pyrazolone, isolating said salt by filtering, heating said salt with a solution of caustic soda for a relatively long period of time, extracting said resultant mixture while it is still warm with benzene, and then removing the benzene to 25 isolate the desired product.

9. A process for producing 1-phenyl-2,3-dimethyl-5-pyrazolone which comprises the steps of reacting 1-phenyl-3-methyl-5-pyrazolone with p-toluene-sulphonic-acid-methyl-ester in the absence of a solvent at an elevated temperature, thereby producing a melt containing quaternary bases, treating said melt with an excess amount of a compound of the group consisting of an alkali-metal hydroxide and an alkali-metal carbonate at a temperature of substantially 100° C. for a relatively long period of time in order to convert said quaternary bases into the desired product, extracting the mixture while it is still warm with benzene, and then removing the benzene to 35 isolate the product.

10. A process for producing 1-phenyl-2,3-dimethyl-5-pyrazolone which comprises the steps of reacting 1-phenyl-3-methyl-5-pyrazolone with p-toluene-sulphonic-acid-methyl-ester in the absence of a solvent at an elevated temperature, thereby producing a melt, dissolving said melt, adding a solution of caustic alkali thereto, extracting said mixture with benzene, separating out the quaternary bases formed by the reaction which are still present in the mixture, treating said quaternary bases with an excess amount of a compound of the group consisting of an alkali-metal hydroxide and an alkali-metal carbonate at substantially 100° C. for a relatively long period 55 of time in order to convert said bases into the desired product, extracting said resulting mixture while it is still warm with benzene, and then removing the benzene in order to isolate the desired product.

11. A process for producing 1-phenyl-2,3-dimethyl-5-pyrazolone which comprises the steps of reacting 1-phenyl-3-methyl-5-pyrazolone with dimethyl sulphate in the absence of a solvent at an elevated temperature, thereby producing a melt containing quaternary bases, treating said melt with an excess amount of a compound of the group consisting of an alkali-metal hydroxide and an alkali-metal carbonate at a temperature of substantially 100° C. for a relatively long period 65 of time in order to convert said quaternary bases into the desired product, extracting the resultant mixture while still warm with benzene, and then removing the benzene to isolate the desired product.

12. A process for producing 1-phenyl-2,3-dimethyl-5-pyrazolone which comprises the steps of reacting 1-phenyl-3-methyl-5-pyrazolone with dimethyl sulphate in the absence of a solvent at 5 an elevated temperature, thereby producing a melt, dissolving said melt, adding thereto a solution of a caustic alkali, extracting the resultant mixture with benzene, separating out the quaternary bases formed as a result of the reaction, 10 treating said quaternary bases with an excess amount of a compound of the group consisting of an alkali-metal hydroxide and an alkali-metal carbonate, cooling the resulting solution, acidulating said solution, crystallizing out a second recovered portion of said p-toluene-sulphonate of the 1-phenyl-2,3-dimethyl-5-pyrazolone base, mixing said two 15 separately recovered crystallized portions of the sulphonate, heating the solution with a mixture of caustic alkali for a relatively long period of time, extracting the resulting solution while still warm with benzene, and then removing the benzene to isolate the product.
13. A process for producing 1-phenyl-2,3-dimethyl-5-pyrazolone which comprises the steps of reacting 1-phenyl-3-methyl-5-pyrazolone with p-toluene-sulphonic-acid-methyl-ester in the absence of a solvent at an elevated temperature 20
- thereby producing a melt, dissolving said melt in hot water, acidulating the resulting solution, cooling said mixture in order to crystallize the first recovered portion of the p-toluene-sulphonate of the 1-phenyl-2,3-dimethyl-5-pyrazolone base, filtering off the said crystallized sulphonate, concentrating the filtrate obtained, heating said filtrate for a relatively long period of time at substantially 100° C. with an excess amount of a compound of the group consisting of an alkali-metal hydroxide and an alkali-metal carbonate, 10 cooling the resulting solution, acidulating said solution, crystallizing out a second recovered portion of said p-toluene-sulphonate of the 1-phenyl-2,3-dimethyl-5-pyrazolone base, mixing said two 15 separately recovered crystallized portions of the sulphonate, heating the solution with a mixture of caustic alkali for a relatively long period of time, extracting the resulting solution while still warm with benzene, and then removing the benzene to recover the desired product.

BAPTIST REUTER.
